United States Patent Office

Des. 227,304
Patented June 12, 1973

227,304

SUNGLASS FRAME FRONT

Roger L. McCracken, Chili, N.Y., assignor to Bausch & Lomb Incorporated, Rochester, N.Y.

Original design application Dec. 31, 1969, Ser. No. 20,715, now abandoned. Divided and this application Dec. 2, 1970, Ser. No. 26,252

Term of patent 14 years

Int. Cl. D16—06

U.S. Cl. D57—1 D

FIG. 1

FIG. 2

FIG. 3

FIG. 1 is a front view of a sunglasses frame front showing my new design;

FIG. 2 is a side view thereof as taken from the right of FIG. 1, the opposite side being identical; and

FIG. 3 is a top plan view thereof.

This is a division of design application Ser. No. D. 20,715, filed Dec. 31, 1969 and now abandoned.

I claim:

The ornamental design for a sunglasses frame front, substantially as shown and described.
